UNITED STATES PATENT OFFICE.

JOHN E. CHRISTENSEN, OF CHICAGO, ILLINOIS.

SOUND-AMPLIFIER FOR TALKING-MACHINE.

1,358,706.

Specification of Letters Patent. Patented Nov. 16, 1920.

Application filed May 19, 1919. Serial No. 298,221.

To all whom it may concern:

Be it known that I, JOHN E. CHRISTENSEN, a citizen of the United States, residing at Chicago, in the county of Cook and State of Illinois, have invented new and useful Improvements in Sound-Amplifiers for Talking-Machines, of which the following is a specification.

This invention relates to sound amplifiers or horns employed in connection with phonographs and other sound reproducing machines, and its object is to provide a horn of novel and improved construction, and design, whereby the sounds are rendered soft and mellow, and all harsh noises are eliminated or reduced to a minimum.

The object stated is attained by means of a combination and arrangement of parts to be hereinafter described and claimed, and in order that the same may be better understood, reference is had to the accompanying drawing forming a part of this specification.

In the drawing, Figure 1 is a longitudinal section of the horn, and

Fig. 2 is a cross-section thereof.

Referring specifically to the drawings, the horn or sound amplifier is a resonant double-walled structure of thin wood of such quality as is used in violin, guitar and similar musical instruments having a hollow resonant body. The outer wall of the horn is shown at 5 and the inner wall at 6, these walls being spaced to provide an air chamber 7 which is closed at the outer end of the horn by a transverse wall 8, extending between the walls 5 and 6 at this end of the horn. The inner end of the air chamber 40 is also closed by a transverse wall 8a. The walls 5 and 6 converge rearwardly and the air chamber is therefore flared toward the outer end of the horn.

The shape of the horn, in cross-section, is, preferably square, and it is flared in the direction of the outer end.

A suitable distance back of the outer end of the horn, the inner wall 6 has a pair of aligned opposite openings 9 forming sound holes which open from the interior of the horn into the air chamber 7 surrounding the same. The air chamber is therefore completely closed in except where it opens into the interior of the horn.

55 The sound emitted by the horn may be further modified by providing a means for

partly or completely closing the sound holes 9, the same comprising a pair of damper slides 10 carried by the branches 11 of a fork which straddles the opposite walls 6 60 in which the sound holes are made. The fork branches pass loosely through apertures in opposite portions of the walls 5, and on the outside of the horn they are connected to an operating handle 12. By sliding the fork transversely of the horn, inwardly or outwardly, the slides 10 are readily positioned to cover or uncover the sound holes 9 to obtain the desired tone quality. When the horn is built into a cabinet, it will 70 be understood that the handle 12 must project through an aperture in the wall of the same.

The fork branches 11 are slightly resilient so that the slides are held snugly in contact 75 with the wall 6.

To limit the stroke of the slides, the portions of the fork branches extending across the space between the walls 5 and 6, are fitted with two spaced abutments composed 80 of felt washers 13 held against inward movement by suitable means, such as cotter pins 14. Thus one or the other of a pair of washers strikes the walls 5 and 6 as the fork is shifted, making the action noiseless, and 85 saving the parts from being scratched or marred.

To the rear or inner end of the horn is secured an elbow 15 having a sound conduit 16 opening into the horn. Where this end 90 of the horn meets the elbow, top and side reinforcing blocks 17 and 18, respectively, are glued over the joint.

The upper end of the elbow 15 may be secured to the base board 19 which supports 95 the turn-table, the sound arm being fitted to the elbow in the usual manner.

By the construction hereinbefore described a hollow resonant body is provided for the horn, said body being similar to the 100 body of a violin, guitar or other stringed musical instrument, and the sounds passing through the horn are considerably modified, their qualities being improved.

I claim:

1. A talking machine horn having a hollow resonant body formed by spaced inner and outer walls, with sound holes in opposite portions of the inner wall and opening into the space between the inner and outer walls, dampers controlling the sound holes, and a fork straddling the opposite walls 110

having the sound holes and carrying the dampers, the branches of the fork having an actuating handle passing through the outer wall.

5 2. A talking machine horn having a hollow resonant body formed by spaced inner and outer walls, with sound holes in opposite portions of the inner wall and opening into the space between the inner and outer 10 walls, dampers controlling the sound holes,

and a fork straddling the opposite walls having the sound holes and carrying the dampers, the branches of the fork having an actuating handle passing through the outer wall and provided between said wall 15 and the inner wall with stops to limit the travel of the fork.

In testimony whereof I affix my signature.

JOHN E. CHRISTENSEN,
